UNITED STATES PATENT OFFICE

JAMES E. FOULKS, OF BRIGHTWATERS, NEW YORK, ASSIGNOR TO CLIMAX STATIONERY COMPANY, INC., OF NEW YORK, N. Y., A CORPORATION OF NEW YORK

MEANS FOR BINDING SHEETS

Application filed January 21, 1927. Serial No. 162,631.

This invention relates to the binding of loose sheets and particularly sheets of different sizes, and it is the object of the invention to provide an improved method and 5 means for assembling and binding the sheets in a sheet body and the mounting of the sheet body in a binding body, and to provide a method and means by which loose sheets may not only be more readily and 10 easily bound, but in a less expensive and more efficient manner.

A further object of the invention relates to improved binders to be engaged in the perforations of sheets to be bound to assemble 15 the sheets in a sheet body on said binders, and means engaged or interlocked with the free ends of the binders at opposite sides of the sheet body assembled thereon to retain the sheet body assembled on the binders.

20 In carrying out the invention binders comprising strips of laterally pliable and edge-wise stiff and readily severable material are folded upon themselves with a loop arranged at the fold, although this is not absolutely

25 essential, with the ends of the strip extending in parallel and contiguous relation, an abutment in the form of a pin being engaged in the fold, or within said fold in a tubular member having a lateral slot for lateral engagement onto the binder strip. The sheets to be bound are previously provided 30 adjacent to one edge with spaced perforations conforming to the cross sectional shape of the binders, the binders being engaged

35 in said perforations to assemble the sheets thereon to form a sheet body with the loop arranged at the fold of the strips, or said loop engaged in the tubular member, abutting against one side of the sheet body the 40 strips being of a length to extend beyond the opposite side of the sheet body. The free ends of the binder strip at the opposite side of the sheet body are then severed to a pre-determined length and each end folded upon

45 itself when a longitudinally split tubular member is engaged thereon similar to the tubular member engaged upon the loop at the fold of the strip, and an abutment pin is then engaged in said tubular member to 50 co-operate with the folded strip ends to

secure the tubular member thereon and retain the sheets assembled upon the binders. Should the sheets constituting the sheet body so bound be of irregular size the marginal portions of the sheet body are trimmed and 55 the bound sheets in such condition may be stored away for future reference. If desired, the sheet body may be mounted in a binding body comprising a back with cover or leaf sections connected thereto, said binding body being arranged with alined and spaced tubular members in the region of the juncture of the cover sections with the back with which the tubular members on the binders of the sheet body are interlocked by 60 inserting the bound sheet body between the cover sections and interengaging or interposing said tubular members in the spaces between and in line with the tubular members on the binding body and then engaging 65 pintles in the alined tubular members, said tubular members being in the nature of knuckles.

In the drawings accompanying and forming 70 a part of this specification Figure 1 is an end elevational view of a binding body showing the arrangement of a bound sheet body mounted therein.

Figure 2 is a cross sectional view on an enlarged scale taken on the line 2—2 of Figure 1 looking in the direction of the arrows.

Figure 3 is a fragmentary sectional view taken on the line 3—3 of Figure 1 looking in the direction of the arrows.

Figure 4 is a perspective view to show 85 the mounting of the binders of the sheet body on mounting plates constituting a part of the binding body.

Figure 5 is a fragmentary end view showing 90 the cover sections of the binding body in open position as well as the sheets of the sheet body to show the manner in which a spreading force of the sheets exerts a binding and clamping force upon the sheets 95 of the sheet body.

Figure 6 is an end elevation of a binder with the tubular members engaged thereon to retain the sheets in assembled position 100 on the binders.

Figure 7 is a perspective view of the strip from which the binders are formed.

Figure 8 is a perspective view of the strip showing the same as arranged to form the binder.

5 Figure 9 is a fragmentary view of a sheet showing an arrangement of a perforation therein.

10 Figure 10 is a perspective view of one of the tubular members or knuckles for engagement on the binders to retain the sheets of the sheet body assembled on the binders.

15 Figure 11 is a fragmentary perspective view showing the manner of assembling the sheets on the binders; and

20 Figures 12 to 18, inclusive, are a series of views in perspective showing the successive steps of the operation of folding the free ends of the binders preparatory to the engagement of a tubular member or knuckle thereon.

25 In the embodiment of the invention the sheets S are first arranged with spaced perforations 19 along one marginal portion. These perforations may be of any desired number, four being in the arrangement of binding means illustrated. The sheets of the sheet body are bound together by binders engaged in the sheet perforations to assemble the sheets on the binders to form a sheet body.

30 The binders comprise a strip 23, as shown in Figure 7, of flat laterally pliable though edgewise stiff material, such as brass or copper, the strip being folded upon itself and arranged with a loop portion 24 at the fold, the two folded portions 25 extending in contiguous parallel relation from the loop portion, as shown in Figure 8. The sheets are 35 assembled on said binders as shown in Figure 11 with the loop portion abutting against one side of the sheet body with the free ends extending beyond the side of the sheet body opposite to that against which the loop portion of the binders abuts. The free ends of the binders are severed, as by a pair of shears, to a predetermined length. To assure the severing of the ends at the proper length a gauge member 26 is provided. This 40 gauge member is constructed of a sheet metal plate of rectangular shape with a central slot 27 cut into one end and terminating within the body of the plate. The opposite end of the plate is arranged with a reduced portion 30. The plate is folded upon itself so that the reduced portion 30 will overlie a portion of the slot 27, as shown in Figures 45 12, 13 and 14. The folded end is bent to extend at a right angle to the body, as at 28. 50 In practice the gauge is engaged flat upon the sheet body with the projecting ends of the binders engaged in the slot 27 in abutting relation to the end of the reduced portion 30, the ends of the body being severed 55 at a predetermined point so that the portion

of the binder ends extending from the top of the sheet body is equal in length to the height of the bent portion 28 of the gauge. The extended ends are then spread or bent laterally from the gauge portion at opposite sides of the slot 27, as at *a* in Figure 13. The gauge member is then moved forward so that the reduced portion 30, which is in the nature of a projection or tongue, will overlie and be contiguous to the spread ends of the binder. The ends are then bent inwardly upon themselves over the projection or tongue 30, as at *b* in Figure 14, when the reduced portion of the gauge member is withdrawn from engagement within the bent ends and they are forced together by a suitable tool, such as a hammer, thereby forming an abutment against the side of the sheet body, as at *c* in Figure 15.

55 To retain the sheet body in assembled position on the binders, knuckles 31 in the form of tubular members having a slot 32 cut into one end and terminating adjacent the opposite end, are engaged laterally upon the ends of the binders with the loop portion 24 within one knuckle and the folded ends within the other knuckle, as shown in Figure 6. The size of the knuckles is such that they can be readily slid over the loop portion of the binders. In order that the 60 knuckles may be engaged over the folded extended end of the binder the folded portions *c* are bent up to slightly curved form in cross section by any suitable means, as shown at *d* in Figure 16, when one end portion is folded or pinched together to permit of inserting the same into the slotted end of a tubular member or knuckle, as at *e* in Figure 17, and the material being pliable as force is applied to the knuckle to slide 65 it onto the folded end of a binder the material will readily form itself for engagement in the knuckle. After the knuckle has been engaged upon the folded ends of the binder an abutment is engaged in the 70 knuckle in interposed relation to said folded ends, said abutment being in the form of a pointed pintle 37' shaping the folded binder ends as shown at *f* in Figure 18 facilitating the ready removal and engagement of the 75 knuckle thereon. A similar pintle is engaged in the loop 24 of the binder within the knuckle. These abutments firmly clamp the portions of the binder within the knuckles and secure the latter upon the binders and prevent any strain which may be applied to the binders, as by moving the bound sheets to open position and applying a force upon the open and spread sheets, from pulling the binders from the knuckles. 80 While it is not absolutely essential to apply a knuckle member upon the loop of the binders, it is preferable as it adds strength to the binder.

85 The method of binding as described is

particularly adapted for the binding of loose sheets of irregular sizes and after the sheets have been assembled and secured upon the binder into a sheet body the irregular edges of the sheet body are trimmed or cut off in an ordinary paper cutter and thus squaring all of the edges. The bound sheet body in such form may be filed away for future reference.

Should it be desired the sheet body bound on the binders as described may be mounted or bound in a binding body or cover as shown in Figure 1. For this purpose there is provided a binding body or cover comprising a back 20 of curved form in cross section and a pair of cover sections or leaves 21 movably connected to the back, as at 22, in the present instance by a covering material, such as canvas or buckram, for the back and cover leaves, the back and cover leaves being constructed of a rigid material, such as cardboard or binder's board.

To mount the sheet body assembled on the binders in the binding body the latter is arranged with two rows of spaced and alined knuckles or tubular members in the region of the juncture of the cover leaves with the back with which the knuckle members 31 on the binders are adapted to be interlocked.

For this purpose there is provided a pair of plates 33 having portions stamped therefrom to form recesses 34 extending inward from one longitudinal edge and the plate is provided with tongues 35 the outer marginal portion of which are rolled to form the knuckles, as shown at 36. The plates so formed are provided with perforations 37 through which means are inserted for connecting the plates to the back with the knuckles to extend longitudinally and forwardly of the longitudinal marginal portions of the back, as clearly shown in Figure 1, by means of rivets engaged in the plate perforations and correspondingly arranged perforations in the back. In this arrangement the pintles or abutments engaged within the binder knuckles also serve to mount and secure the bound sheet body in the binding body. In the mounting of the sheet body in the binding body all that is necessary is to insert the sheet body between the cover leaves and the knuckles 31 interengaged with the plate knuckles 36 by positioning the knuckles 31 in the recesses 34 in alined relation with the plate knuckles, when the pintle 37 in the form of a rod is inserted into the alined openings in the knuckles, and in effect provides a hinged connection between the bound sheet body and the binding body.

By this arrangement as the cover leaves are moved to open position, as shown in Figure 5, the sheets or leaves of the sheet body spread to position to lie contiguous to the cover and substantially flat and any pressure which may be applied to the opposite

spread portions of the sheet body, or the compression force with which the knuckle members hold the sheets of the sheet body upon the binders, is increased, this being due to the slight flexing of the binders in the direction of the strain and the drawing of the sheets more firmly together through the flexing pull on the binders. The force of said pull is applied upon the sheets through the knuckle members on the binders and the knuckles formed on the plates carried by the back of the binding body.

The bound sheet body may be removably mounted in the binding body by making the pintle rod 37 of such length that one end will project from the knuckle plate 36 at the end of the plate. However, to prevent the ready removal of the sheet body from the binding body the knuckle at the one end of the plates 33 is arranged as a blind knuckle, as shown at 39 in Figure 3, and the pintle rods are of less length than the knuckle carrying plates, and as said rods are engaged in the knuckles they are driven therein by a suitable implement so that the one end will be in engagement with the obstruction in the end plate knuckle, and the other end of the pintle will terminate within the plate knuckle at the opposite end of the plate, as shown at 40 in Figure 2.

While I have illustrated one embodiment of means for a method of binding loose leaf sheets in a sheet body and the mounting of the bound sheet body in a binding body it will be obvious that various modifications may be made in the construction and arrangement of parts without departing from the scope of the invention and that portions of the invention may be used without others and come within the scope of the invention.

Having thus described my invention I claim:

1. In a binder for perforated loose sheets, a strip of flexible material inserted in the sheet perforations with the ends of the strip extending beyond the opposite sides of the assembled sheet body, slotted tubular members engaged upon the ends of the strip, and means engaged in said tubular members to co-operate with the portions of the strip within the tubular members to secure the strip to the latter.

2. A binder as claimed in claim 1, wherein the slot in the tubular members extends only for a portion of the length thereof and said members are adapted to be engaged laterally onto the strip.

3. A binder as claimed in claim 1, wherein the strip is folded upon itself with the opposite end portions extending in contiguous and parallel relation to form the binder and arranged with a loop at the fold for the engagement thereon of the slotted tubular member, and the means inserted in said tubular member to secure the same on the

- loop of the binder strip is engaged in said loop within the tubular member.
4. A binder as claimed in claim 1, wherein the strip is folded upon itself and arranged with a loop at the fold for the engagement thereon of the slotted tubular member, and the means for engagement in the tubular member to secure said member on the binder strip comprises pintles one of which is engaged in the looped fold of the strip in the tubular member.
5. A binding device comprising a relatively thin flat strip of laterally pliable and edgewise stiff material folded upon itself intermediate the ends with the opposite end portions extending in the same direction in contiguous and parallel relation and arranged with an open loop portion at the fold.
- 20 6. A binding device comprising a strip of flat pliable material folded upon itself with the opposite end portions extending in contiguous and parallel relation, and a tubular member having a longitudinal slot 25 for engagement over the fold of the strip and adapted for engagement of a pintle therein within the fold of the strip.
7. A binding device as claimed in claim 6, wherein the folded portion of the strip 30 to be engaged within the tubular member is of open loop form, and the slot in the tubular member extends for only a portion of the length thereof for limiting the movement of said member onto the strip.
- 35 8. In a binder for perforated sheets, a binding body, binders each comprising a strip of pliable material folded upon itself engaged in the sheet perforations to assemble the sheets thereon, knuckle members 40 engaged upon the free ends of the strips, and plates mounted upon the binding body arranged with spaced knuckles for the engagement of the said knuckle members therebetween, and means engaged in the binder 45 and plate knuckles for connection of the sheet body assembled on the binders with the binding body, and said means co-operating with the portions of the binder strips in the knuckles to secure the knuckles on the binders.
- 50 9. In a binder for perforated sheets, a binding body arranged with alined knuckle members, binder strips of pliable material engaged in the sheet perforations to assemble the sheets in the sheet body thereon, and knuckle members adapted for removable engagement upon the ends of the binder strips to abut the outer sheets of the sheet body to retain the sheets assembled on said 55 strips in a compressed condition, and said knuckle members adapted to be interlocked with the knuckle members on the binding body.
- 60 10. In a binder for perforated sheets, a binding body arranged with alined knuckle
- members, binder strips of pliable material engaged in the sheet perforations to assemble the sheets in a sheet body thereon, knuckle members removably engaged upon the ends of the binder strips to abut the outer sheets of the sheet body to retain the sheets assembled on the binders under an adjustable compression, said knuckles being adapted for engagement between the knuckles on the binding body, and means adapted to be engaged in the knuckles for uniting the assembled sheet body with the binding body.
11. In a binding for perforated sheets, binders inserted in the sheet perforations and having sheets assembled thereon to form a sheet body, comprising a strip of pliable material folded upon itself and arranged at the fold with a loop portion for abutment against one side of the sheet body, the folded body portions extending parallelly therefrom through the sheet perforations, the free ends of the body portions extending from one side of the sheets spread and folded upon themselves, knuckles engaged upon the tubular portion and free ends of the binders, and plates adapted for mounting on a binding body arranged for connection of the knuckles therewith for mounting the sheet body assembled on the binders in the binding body.
12. A binding body arranged with a back and a pair of covers movably connected therewith having a perforated sheet body interposed between said covers, binders of pliable material engaged in the perforations of the sheet body with the ends extending beyond the sides of the body, knuckle members arranged for lateral slidable engagement onto the extended ends of the binders, mounting plates carried by the back arranged with spaced knuckle members interengaged with the binder knuckles, and pintles engaged in the knuckles to mount the sheet body in the binding body.
13. In a binder for perforated loose sheets, parallel strips of edgewise stiff and laterally pliable material inserted in the sheet perforations with the ends of the strips extending beyond the opposite sides of the assembled sheet body, slotted tubular members engaged upon the ends of the strips, and means engaged in said tubular members to co-operate with the portions of the strips within the tubular members to secure the strips in the tubular members.
- Signed at the city of New York, in the county of New York and State of New York this 20th day of December, 1926.
- JAMES E. FOULKS.
